UNITED STATES PATENT OFFICE

158,235

POOL BALL RACK

Alfred Richard Van Horne, Albany, N. Y.

Application November 30, 1948, Serial No. 149,872

Term of patent 14 years

(Cl. D34—5)

To all whom it may concern:

Be it known that I, Alfred Richard Van Horne, a citizen of the United States of America, and a resident of Albany, in the county of Albany and State of New York, have invented a new, original, and ornamental Design for Pool Ball Rack, of which the following is a specification, reference being had to the accompanying drawing, forming part thereof, in which:

Fig. 1 is a plan view of a pool ball rack embodying my design.

Fig. 2 is a side view thereof.

Fig. 3 is an end view.

I claim:

The ornamental design for a pool ball rack, as shown.

ALFRED RICHARD VAN HORNE.
